MULTIPLE UNIT DEEP FAT FRYER

Ronald A. Miller, George W. Church, Jr., and Glenn L. Williams, San Antonio, Tex., assignors to Church's Fried Chicken, Inc.

Filed Feb. 22, 1972, Ser. No. 228,459

Term of patent 14 years

Int. Cl. D7—02

U.S. Cl. D55—1 E

Fig. 1

Fig. 2

FIG. 1 is a top view of a multiple unit deep fat fryer showing our new design;

FIG. 2 is a front elevation thereof; and

FIG. 3 is a perspective view thereof.

The undisclosed side and rear are substantially flat and plain.

We claim:

The ornamental design for a multiple unit deep fat fryer, as shown and described.
